UNITED STATES PATENT OFFICE.

SUSANNA B. TRAPP, OF NEW YORK, N. Y.

SAFETY APPLIANCE FOR ELEVATORS.

SPECIFICATION forming part of Letters Patent No. 725,892, dated April 21, 1903.

Application filed August 5, 1902. Serial No. 118,456. (No model.)

To all whom it may concern:

Be it known that I, SUSANNA B. TRAPP, a citizen of the United States, and a resident of New York, in the county of New York and 5 State of New York, have invented certain new and useful Improvements in Safety Appliances for Elevators, of which the following is a specification.

The invention relates to improvements in 10 safety appliances for elevators; and it consists in the novel features, arrangements, and combinations of parts hereinafter described, and particularly pointed out in the claims.

The present invention comprises certain 15 improvements on safety appliances described and claimed in Letters Patent No. 634,966, granted October 17, 1899, to Susanna B. Trapp, and No. 700,458, granted May 20, 1902, to Susanna B. Trapp, and said invention per- 20 tains more especially to two novel features, one being the novel construction and arrangement of the air cushioning cylinder or cylinders by which the car or hoist is arrested in case of accident, and the other feature relat- 25 ing to the novel construction of hoisting-frame for carrying, if desired, the passenger-car, and which frame comprises as integral structural parts the air cushioning-cylinders, the latter being exterior to the car and constitut- 30 ing standards or pillars connecting or aiding in connecting and strengthening and forming parts of the hoisting-frame, which may or may not be equipped with a passenger-car, as may be preferred. When the hoisting-frame 35 is equipped with a passenger - car, the air cushioning-cylinders will preferably be exte- rior to said car and not in the same.

The invention will be fully understood from the detailed description hereinafter present- 40 ed, reference being had to the accompanying drawings, in which—

Figure 1 is a central vertical section, partly broken away, of one of the air cushioning-cylinders with its inclosed parts. Fig. 2 is a like 45 view of the lower portion of said cylinder and illustrates the lower end of the piston-rod projecting downwardly through the lower end of said cylinder. Fig. 3 is a detached view, partly in section, of a portion of one of the 50 air-equalizing pipes connecting the two cushioning-cylinders and equipped with an automatic valve adapted to open downwardly

against the stress of the spring under atmos- 55 pheric pressure when a vacuum is formed in the upper ends of said cylinders. Fig. 4 is a sectional view, on a smaller scale, of a portion of the piston-rod and its inclosed parts. Fig. 5 is a side elevation of the hoisting-frame, the piston-rods being partly broken away. Fig. 6 is a sectional view of same on the dot- 60 ted line 6 6 of Fig. 5. Fig. 7 is a top view of the upper end of the hoisting-frame. Fig. 8 is a horizontal section through a portion of an elevator-car, showing a slightly-modified ar- 65 rangement of the cushioning-cylinders, this 70 modification consisting in placing the cushioning-cylinders at the opposite sides of the hoisting-frame instead of at the corners there- 75 of, as shown in Fig. 6; and Fig. 9 is a horizontal section through a portion of an eleva- 80 tor-car, showing a slight further modification of the invention, the cushioning-cylinders in this instance being at the corners of the car and the usual guides for directing the hoist- 85 ing through the shaft being at the sides of the hoisting-frame in lieu of at the corners thereof, as shown in Figs. 6 and 8.

I have omitted from the drawings the stops located at the several floors of the building to be engaged in case of accident by the pis- 80 ton-rods of the cushioning-cylinders, since said stops form no part of the present invention and are fully illustrated and described in the aforesaid Letters Patent No. 700,458, dated May 20, 1902. 85

In the drawings, 15 15 designate the cushioning-cylinders. 16 denotes the lower hori- 90 zontal beam of the hoisting-frame; 17, the upper horizontal beam of said frame; 18, the hoisting-cables, whose pulleys are mounted 95 between the opposite sides of the said beam 17, and 19 the equalizing and relief pipes connecting the upper ends of the cylinders 15. The pipes 19 afford free communication from one cylinder 15 to the other cylinder 15, and 95 each pipe is provided with an upwardly-act- 100 ing valve 20, mounted within a valve-casing 21, connected with the pipe 19, the said valve 20 being firmly held against its seat by means of a coiled spring 22. The valves 20 only act when by reason of a vacuum that may be formed within the upper ends of the cylinders 15 the pressure of the atmosphere causes the depression of said valve in opposition to

the force exerted by the spring 22 for the purpose of relieving said vacuum.

The cylinders 15 are plain straight vertical tubular columns and have upon their upper 5 ends the caps 23, Fig. 1, and upon their lower ends the caps 24, Fig. 2, said caps being secured by screw-threads upon the ends of said cylinders and in addition being further secured by means hereinafter specified. The 10 upper caps 23 are provided with the central domes 25 and oil-cups 26, and in addition the said caps 23 are apertured to receive the ends of the equalizing-pipes 19. The lower ends of the caps 23 are formed with the annular 15 shoulders or flanges 27, which receive the circular ends 28, secured at the ends of the upper horizontal beam 17, said ends 28 fitting upon the caps 23 and against the shoulders 27 and connecting the cylinder 15 at one corner 20 of the hoisting-frame with the cylinder 15 at the other corner of said frame, as illustrated in Figs. 5 and 7. The cylinders 15 thus become the corner-posts for the hoisting-frame and receive and support the upper 25 connecting-beam 17, formed of girders. The caps 24 at the lower ends of the cylinders 15 are seated upon the end portions of the channel lower beam 16, as shown in Fig. 2, and are secured upon said beam by means of the 30 series of bolts 29, extending through lugs 30, formed on said caps 24 and engaging said beam 16. The end portions of the beam 16 are supported upon frames 31, which are connected with the circular end portions 28 of the upper 35 beam 17 by means of the vertical tie-bolts 32, which pass through lugs formed on said portions 28 and through lugs formed on the frames 31, the tie-bolts 32 being, as shown in Fig. 7, at the opposite sides of the cylinders 15. 40 The hoisting-frame thus comprises as its main feature the lower beam 16, upper beam 17, vertical cylinders 15, frames 31, and tie-bolts 32, and the frame thus constructed is of great durability, simplicity, and efficiency, 45 and in its construction the cylinders 15 answer not only as cushioning-cylinders, but as vertical columns or standards intermediate the upper and lower beams of the frame. In addition to this the method described for constructing the hoisting-frame enables the efficient securing of the upper and lower caps upon the cylinders 15 by means which also 50 add to the rigidity and durability of the frame as a whole. The cushioning-cylinders 15, while operating as cushioning-cylinders, constitute a portion of the hoisting-frame as distinguished from merely being seated upon said frame. The hoisting-frame will be provided with any suitable flooring or with any 55 suitable passenger-car when it is desired that a car shall be employed. When a passenger-car is employed, it will be of such outline as to fit between the cushioning-cylinders 15, so that said cylinders shall not be 60 exposed in the car, but will be exterior thereto, as illustrated in Figs. 8 and 9, it being my purpose that the elevator-car shall ex-

clude the cushioning-cylinders and all apparatus not required to be in the car.

The shoes for directing the movement of 70 the hoisting-frame by their engagement with the usual tracks or guides 34, provided in the elevator-shafts, are numbered 35, and preferably these shoes are in the form of suitably-secured casings having vertical grooves 75 to engage the flanges of the guides 34, as illustrated in Figs. 6 and 7. When the guides 34 are secured under conditions that may prevail otherwise than as shown in Figs. 6 and 7, they may be arranged as shown in Figs. 80 8 and 9. In Fig. 8 the shoes 35 are illustrated as being secured to the corners of the car-hoisting frame, because the cushioning-cylinders 15 are not at the corners of the hoisting-frame, and in Fig. 9 the shoes 35 are illustrated as secured to the opposite sides of the car or hoisting-frame, although the cushioning-cylinders are at the corners of and constitute a portion of the hoisting-frame.

The lower beam 16 above referred to is 90 commonly called a "safety-plank," and the upper beam 17 is formed, as shown in Fig. 7, of two parallel bars or girders, to whose ends are secured the end pieces 28, which are in the form of circular frames fitting upon the 95 upper caps 23 of the cylinders 15.

In Figs. 5 and 6 I illustrate the angle-iron frames 70 70 as a means for securing an elevator-car 33 upon the safety-plank 16 of the hoisting-frame, these angle-iron frames 70 100 being riveted at their ends to the flanges of the beam or safety-plank 16, as illustrated in Fig. 6, and at their outer sides being secured by rods 71 to the end portions 28 of the upper beam or girders 17, as shown in Figs. 5 and 105 6. The angle-iron frames 70 and sustaining-rod 71 constitute one convenient means for supporting an elevator or passenger car, and I do not limit my invention to such frames and rods. When the frames 70 are employed, 110 the lower end of the elevator-car 33 will set upon said frames and be bolted or otherwise secured thereto.

Within each cushioning-cylinder 15 is provided a piston 40, having secured thereto a 115 hollow piston-rod 41, projecting downwardly through an opening in the lower cap 24 and through an opening in the beam 16 directly below said cap. The upper end of the piston-rod 41 is threaded to engage a threaded 120 receiving-socket 42 in the lower end of the piston 40, and the lower end of the piston-rod 41 is closed by a durable cap or plug 43, which is screwed into the lower end of said piston-rod and becomes a part thereof. The 125 piston-rod 41 is open at its upper end to receive the lower end of the perforated pipe 44, which extends above and below the piston 40 and passes through a closely-fitting aperture 45, extending through a stuffing-box construction 46, fitted within the central portion of said piston. The lower end of the perforated pipe 44 will be closed by the cap 47, and the upper end of said pipe 44 will be closed

by a cap 48. The upper portion of the piston 40 is encompassed by the packing-rings 49, fitting within grooves formed in said piston, and these grooves communicate, by means of 5 apertures 50, with the interior of the upper portion of the cylinder 15, so that when the air is compressed in the upper portion of the cylinder 15 the pressure of the air may be exerted through said apertures 50 against the 10 packing-rings 49 to insure their firm air-tight contact with the inner walls of the cylinder 15, thereby the more assuredly trapping and compressing the air in the upper end of the cylinder 15 by the upper movement of the 15 piston 40.

Within the piston-rod 41 is secured an inner tube 51, which is perforated, as shown in Fig. 4, and is separated by an air-space from the inner walls of the piston-rod. Within 20 the inner tube 51 is secured the spring 52, which is upon a rod 53, carrying at its upper end a head 54, which is recessed at its upper end to receive the cap 47 on the lower end of the perforated pipe 44. The tendency of the 25 spring 52 is to press the head 54 upward against the perforated pipe 44, as shown; but said spring 52 is capable of compression when in case of accident the lower end of the piston-rod 41 meets with one of the stops (not 30 shown) and is driven upward thereby. The piston-rod 41 moves with the piston 40, and the inner tube 51 being secured to the piston-rod 41 will move with it; but the head 54 and rod 53 may have an independent movement 35 within the tube 51, and the piston 40 may move independently of the perforated pipe 44. The tube 51 forms, in effect, a cylinder for the head 54, and said tube 51 is perforated, so that at the proper time the air escaping 40 downward through the tube 44 may pass into the chamber formed between said tube 51 and the inner walls of the hollow piston-rod and thence find an escape through the perforations 55, formed in the lower end of the said 45 piston-rod. There are a number of the perforations 55 formed in the lower end of the piston-rod 41, and it is desirable that some means for regulating the extent of the exposure of the openings 55 may be provided, and 50 therefore upon the lower portion of the piston-rod 41 I provide a band 56, containing apertures 57, which may be moved into register with the openings or apertures 55 in the piston-rod 41. The purpose of moving the 55 band 56 is to bring more or less of its apertures 57 into line with the apertures 55 in the piston-rod, so as to regulate the escape of air through said apertures and from the piston-rod. 60 In Figs. 1, 2, and 3 I illustrate the parts within the cylinder 15 in their operating position—that is to say, in said figure I illustrate the said parts in the position that will be given to them by the contact of the lower 65 end of the piston-rod 41 with an obstruction or stop, arresting its downward movement with the hoisting-frame. In the normal safe

running condition of the hoisting-frame the piston 40 will be in the lower end of the cylinder 15, with the piston-rod 41 projecting 70 downwardly through the lower end of said cylinder, and under such condition the lower end of the perforated tube 44, which is, in effect, a valve, is inclosed within the bore 45 of the stuffing-box construction 46, the upper 75 end of the tube 44 then being free of and below the upper end or cap of the said cylinder 15. When in case of accident the lower end of the piston-rod 41 meets an obstruction and is arrested thereby, the hoisting-frame 80 will continue for a brief period to descend, and this will carry the cylinder 15 downward upon the piston 40, whereby air above the piston 40 and in the cylinder 15 will be compressed and operate as a cushion. A move- 85 ment downward of the cylinder 15 upon the piston 40 will also have the effect of carrying the dome 25 at the upper end of the cylinder 15 downward against the upper end of the perforated tube 44, this contact of 90 the dome 25 with the upper end of the tube 44 not taking place until after the air has been compressed in the upper end of the cylinder and it is desired that the car shall settle slowly downward by the release of the 95 air to reach one of the floors of a building. The driving downward of the perforated tube 44 has the effect of causing the lower end of said tube to pass below the stuffing-box 46 and against the head 54, supported upon the 100 spring 52, the latter compressing and some of the apertures in the lower portion of the tube 44 becoming exposed within the upper end of the piston-rod 41, this exposure of the said 105 apertures permitting the escape of the air from the upper end of the cylinder 15 into the upper end of the hollow piston-rod 41, the said air thence passing through the apertures in the inner tube 51 and escaping downward around the outer walls of said inner tube and 110 finally through the uncovered apertures 55 in the lower end of said piston-rod. The parts connected with both cylinders 15 operate in harmony, and since said cylinders are 115 connected by the pipes 19 there will be a uniform compression of the air within the upper ends of said cylinders, and the hoisting-frame will be properly arrested and cushioned. and then, due to the action of the tubes 44, allowed to settle to one of the floors 120 of the building, so that the attendant or passengers may escape at said floor. After the happening of an accident and the arresting of the hoisting-frame the hoisting-frame will be pulled upward, and at the proper time the 125 piston-rods 41 will be pulled downward to their normal position for further use. When pulling the piston-rods 41 downward, the pistons 40 will be drawn thereby to the lower ends of the cylinders 15, and as the pistons 130 40 move downward the springs 52, pressing against the lower ends of the perforated tubes 44, will move said tubes upward until their lower ends are sealed within the stuff-

ing - boxes 46 and the heads 54 above said springs 52 reach the lower end of said stuffing-boxes. The then continued downward movement of the pistons 40 to their normal position will result in said pistons engaging the caps 47 on the lower end of the tubes 44 and pulling said tubes downward from the domes 25, and at such time, the communication from the lower end of said tubes having been cut off, if a vacuum shall be formed in the upper ends of the cylinders 15, due to the drawing downward of the pistons 40, the vacuum - valves 20 will open under atmospheric pressure and the air will pass inward through the pipes 19 and reach the upper portions of the cylinders 15.

From the foregoing description it will be seen that my invention relates more especially to two features, one of said features comprising the cushioning-cylinder and its rod, with the parts inclosed therein, and the other feature pertaining to the hoisting-frame structure, in which the cushioning-cylinders constitute structural parts and are at the opposite ends of the lower beam or safety-plank 16 and upper beam or girders 17.

As will be understood from the foregoing description, the present invention is not limited to the elevator-car 33, which may or may not be used, as may be preferred; but when such car is used it will be secured above the beam or safety-plank 16, and the cylinders 15 will be exterior thereto and not in the same. The stops for arresting the piston-rod 41 may be at the lower end of the elevator-shaft or along the several floors of the building and need not be shown or described herein, since by reference to the aforesaid Letters Patent No. 700,458 satisfactory stops arranged at the several floors of the building and operable by means carried by the hoisting-frame and under the control of the attendant thereon may be fully understood. I have not deemed it necessary, therefore, to specifically refer to either the stops for arresting the piston-rods 41 nor to the means by which the stops when placed at the several floors of the building may be brought into operative position by the attendant on the hoisting-frame, the present invention not being confined to any special character of stops for arresting the piston-rods 41 nor to any special means for giving effect to said stops.

I do not limit the invention to the placing of the cushioning cylinder or cylinders on the hoisting-frame, since the said cylinders may be arranged at the top of the elevator-shaft, as shown in the aforesaid Letters Patent No. 700,458, or at the bottom of said shaft, as shown in the aforesaid Letters Patent No. 634,966; nor do I limit the invention to the employment of atmospheric air in its natural condition within the cushioning-cylinders 15, since when desired I shall employ compressed air in said cylinders in the manner explained in both of the above-mentioned Letters Patent. The lower portions of the cylinders 15

will be provided with vent-apertures 60, such apertures being shown in the aforesaid Letters Patent No. 700,458. The packing-rings 70 49, encircling the piston 40, are preferably of metal.

What I claim as my invention, and desire to secure by Letters Patent, is—

1. The cushioning-cylinder, the piston and 75 the rod secured thereto and projecting from said cylinder for contact with an obstruction, said piston having the aperture or bore 45 through it, combined with the perforated tube 44 mounted in said bore and normally 80 sealed at its lower end, whereby upon the driving of said piston against the air in said cylinder one end of said tube striking the end of the cylinder will force the other end of said tube through said piston to form a 85 release for the air; substantially as set forth.

2. The air cushioning-cylinder, the piston 40, and the piston-rod secured to said piston and projecting through the end of said cylinder, said piston having the bore, combined 90 with the perforated tube 44 having a head at its lower end and at its lower portion normally sealed in said bore, combined with means normally retaining one end portion of said tube within said bore, whereby upon 95 said piston-rod meeting an obstruction the said piston will be driven toward the end of the cylinder to compress the air therein and said tube will strike the end of the cylinder and have its normally sealed end driven 100 through and exposed beyond the end of said bore for releasing the air, and whereby when said piston is returned to its normal position it will engage the head end of said tube and withdraw the same to its normal position; 105 substantially as set forth.

3. The air cushioning-cylinder, the piston therein, and the hollow piston-rod connected with said piston and projecting through the end of said cylinder, said piston having the 110 bore and said piston-rod having outlet-apertures, combined with the perforated tube 44 normally sealed at one end within said bore, the head 54 adapted to engage the extremity 115 of said end of said tube, and the spring engaging said head and concealed within said piston - rod, said spring normally retaining one end of said tube within said bore but yielding when the other end of said tube is pressed against the end of the cylinder during the movement of said piston, whereby the air may be released through said tube; substantially as set forth.

4. The air cushioning-cylinder, the piston therein, and the hollow piston-rod secured to 125 said piston and projecting through the end of said cylinder, said piston having the bore and said piston - rod having the outlet for air, combined with the perforated tube 44 normally sealed at one end within said bore, the 130 inner perforated tube 51 secured within said piston-rod, the head 54 within said tube 51, and the spring also within said tube 51 and pressing against said head, said head and

- spring normally keeping one end of said perforated tube 44 within said bore but yielding to permit said end of said tube 44 to slide through said bore when the other end of said tube strikes the end of said cylinder, thereby permitting air communication through said tube 44 into the said tube 51, whence the air will escape through the perforations in the piston-rod; substantially as set forth.
- 5 5. The air cushioning-cylinders having the pistons and projecting piston-rods, combined with the equalizing-pipe connecting said cylinders, and the vacuum-valve interposed in said pipe; substantially as set forth.
- 10 6. The hoisting-frame comprising lower and upper horizontal beams and the vertical air cushioning-cylinders connected to said beams at their end portions and constituting structural parts of said hoisting-frame, combined with the pistons within said cylinders, and the projecting piston-rods connected with said pistons; substantially as set forth.
- 15 7. The hoisting-frame comprising the lower and upper beams, and the air cushioning-cylinders connected to the ends of said beams and forming structural parts of said frame, the upper beam having end pieces encircling the upper ends of said cylinders, and the ends of the lower beam forming seats for the lower ends of said cylinders, combined with means for fastening the ends of said lower beam to said cylinders, the frames below the ends of said lower beam, and the tie-rods connecting said frames with the end portions of said upper beam; substantially as set forth.
- 20 30 35

8. The hoisting-frame comprising the lower beam 16, the upper girder-beam 17 having the end frame-pieces 28, the air cushioning-cylinders forming structural parts of said hoisting-frame and having caps 23, 24, at their 40.

ends, the said end frames 28 fitting upon said caps 23, and said caps 24 being seated upon the ends of said lower beam, combined with the bolts securing said caps 24 to the said lower beam, the frames 31 below the ends of 45 said lower beam, and the tie-rods connecting said frames 28 to said frames 31; substantially as set forth.

9. The hoisting-frame having the air cushioning-cylinders constituting structural parts 50 thereof and interposed between the upper and lower beams of said frame, said cylinders having the pistons and projecting piston-rods, combined with the car mounted within said frame and having its walls set to 55 the inner sides of said cylinders, thereby excluding said cylinders from within the car; substantially as set forth.

10. The air cushioning-cylinders having the pistons containing the slide-valves, which 60 are operated by the movement of the piston-heads, combined with vacuum-valves and equalizing-pipes; substantially as set forth.

Signed at New York, in the county of New York and State of New York, this 4th day 65 of August, A. D. 1902.
